Attorney

UNITED STATES PATENT OFFICE

OWEN MORRIS BANGS, OF NEW YORK, N. Y.

HINGE

Application filed April 20, 1929. Serial No. 356,675.

The invention relates to hinges, and its object is to prevent unauthorized removal of the hinge from an object to which it is applied. The invention is particularly applicable for use in connection with a hasp lock of the type disclosed in my Patent No. 1,711,339, granted April 30, 1929.

By the use of my invention, hinges may be secured to trunks, suit cases, boxes, bags, freight cars or other devices, in such manner that their removal from the outside by means of a chisel or like tool is rendered much more difficult than at present.

According to my invention, no parts which can be cut or driven out, such as the pintle of the hinge or the securing bolts, are in any way exposed, nor can they be reached in any way from the outside after the device has been assembled. The improved hinge, when combined with the seal lock or latching member disclosed in my Patent No. 1,711,339, is particularly adaptable for use on the doors of containers such as are coming into extensive use for the handling of freight by rail and by express.

The hinge comprises two relatively swinging members, one of said members having a central ear or pintle carrying member, and having a pin or pintle extending laterally through and on each side of said ear, and the other member being split and comprising two parts which have overlapping beveled portions, these parts being adapted, when assembled, to form a single plate. Each part is provided with an ear or socket adapted to receive one of the laterally extending portions of the pin. Each ear is closed on the side opposite the pin receiving aperture, so that when the hinge is in assembled position the pin is entirely inaccessible and cannot be driven out, as can the pintle of an ordinary hinge. Each of the two relatively swinging members has preferably integral therewith a stud or stem adapted to extend through the body of the trunk or other object to which the hinge is applied, and to be fitted with a cap secured on the inside of the trunk or other article. By the combination of these studs and the method of assembling the parts of the hinge itself, the device is entirely pro-

tected on the outside, and cannot be removed without detection.

The invention will be more readily understood by reference to the accompanying drawing, in which

Fig. 1 is a plan view of a hasp lock embodying my improved hinge;

Fig. 2 is a plan view of the keeper of the lock;

Fig. 3 is a sectional view of the keeper showing the integral studs for attaching the same to a trunk or the like;

Fig. 4 is a transverse sectional view through the split member of the hinge showing the beveled overlapping meeting portion;

Fig. 5 is a plan view similar to Fig. 1 showing the invention applied to a hinge other than a portion of the lock;

Fig. 6 is a longitudinal section of the device shown in Fig. 5; and

Fig. 7 is a transverse sectional view of the same showing the overlapping portions of the split member.

Figs. 1 to 4 show the invention in its relation to a hasp lock. According to this embodiment, the reference characters A and B represent the two relatively swinging members of the hinge, one of which is adapted to be engaged in a keeper C and held in place by means of a seal D, while the other is secured to the trunk or other object E, shown in Figs. 3 and 4.

The keeper C is provided with studs 10 extending from the inner side of the flange of the keeper as shown clearly in Fig. 3. These 85 studs are preferably formed integral with the keeper and may be cast therewith. As shown, the studs are threaded both internally as at 11 and externally as at 12. This permits the use of nuts or of bolts for attaching the keeper to the trunk or the like, whichever means may be preferred. The studs 10 cannot be reached from the outside, as they are completely covered by the overlapping flange of the keeper.

The two relatively swinging members A and B are assembled in such a manner that the pintle or pin of the hinge cannot be driven out or cut. As shown, the member A is provided with an ear 13 through which 100

extends a pin 14, such pin having extensions 15 on each side of the ear 13. If desired, the members 15 could be cast integral with the ear 13 instead of being part of the pin as shown. The member B is formed in two parts 16 and 17, both of which are provided with ears 18, which are recessed as at 19 to receive the ends 15 of the pintle or pin 14. The members 16 and 17 are beveled at their meeting portions 20, and when assembled, these beveled portions overlap, as clearly shown in Figs. 1 and 4. This overlapping prevents entrance of a tool such as a chisel or the like. When the parts are assembled as shown in full lines in Fig. 1, it will be noted that the ends of the pin are completely protected by metal as at 22, since the sockets 19 do not extend entirely through the ears 18. Thus it is impossible to drive out the pin from the ends.

As shown in Fig. 4, each of the portions 16 and 17 is provided with an integral stem or stud 23, which extends through the trunk E and which is internally and externally threaded in the same manner as the studs 10. As shown, nuts 24 are employed for holding these studs in place. If desired, however, washers might be employed and headed bolts, not shown, might be screwed internally into the studs 23.

In Fig. 5, the members A' and B' are attached respectively to two movable parts E of the trunk or other object to which the hinge is applied. The member B' is composed of two parts 25 and 26 which are beveled at their meeting portion 27, as in the previously described embodiment of the invention. The member A' is provided with an ear 13 through which extends a pin 14 having extension portions 15 adapted to be received in recessed portions of the parts 25 and 26 of the member B'. The members A' and B' are provided with studs 28, preferably integral therewith and adapted to extend through the trunk E. As shown, the two parts of the split member B' are counter-sunk as at 30, and when the hinge is attached to the trunk, a plate 31 is applied on the outside of the trunk and within the counter-sunk portion of the member B'. This plate extends transversely across the overlapping meeting edges of the parts 25 and 26, and is apertured to permit the studs 28 to pass therethrough. This plate holds parts 25 and 26 in assembled position. On the inside of the trunk, plates 33 and 34 are employed, as shown clearly in Figs. 6 and 7, and nuts 35 on the studs 28 are fastened down on the plates 33 and 34.

Hinges embodying my invention may be manufactured at low cost, and when applied to baggage, freight or the like, will result in rendering the same practically inaccessible to an unauthorized person. The invention may be varied in detail without departing from the scope of the appended claims.

The term "leaf member" in claim 3 is not intended to limit the shape or length of the member. It may be elongated as in Fig. 5, making what is ordinarily termed a strap member. The essential thing is that the lower surface of the member is adapted to rest upon the part to which it is attached. 70

I claim:

1. A hinge comprising two relatively swinging hinge members, one of said swinging members being split and composed of two parts having an overlapping fit at their meeting portions, each of said parts having a stem formed integral therewith, and a removable plate apertured to fit said stems and extending crosswise of said split member, said split member being counter-sunk to receive said cross plate. 75

2. A hinge comprising a member having a pintle carrying portion at one edge, pintle portions at opposite sides of said pintle carrying portion, a sectional member, the sections of which abut one another when assembled along a line that intersects the pintle axis to form a complete plate, and each of two of said sections having a projection at one edge, said projections being spaced from each other when the sections are assembled and having closed sockets in their opposing sides so that the projections embrace the said pintle carrying portion when the members are connected, while the sockets receive and enclose the pintle portions, and means inaccessible from the outside for holding the first named member and the sections of the sectional member 90 against removal from the parts that are to be hinged together. 95

3. A hinge comprising an integral member having a pintle carrying portion at one edge, pintle portions at opposite sides of said pintle carrying portion, a leaf member, comprising disconnected sections which abut one another when assembled along a line that intersects the pintle axis to form a complete plate, and each of two of said sections having a projection at one edge, said projections being spaced from each other when the sections are assembled and having closed sockets in their opposing sides so that the projections embrace the said pintle carrying portion when the members are connected, while the sockets receive and enclose the pintle portions, and means for holding the first named member and the sections of the sectional member 100 against removal from the parts that are to be 105 hinged together. 110

In testimony whereof I affix my signature.
OWEN MORRIS BANGS.
